UNITED STATES PATENT OFFICE.

THOMAS WHITE, OF PEEKSKILL, NEW YORK.

HORSE-DETACHER.

SPECIFICATION forming part of Letters Patent No. 379,352, dated March 13, 1888.

Application filed August 27, 1887. Serial No. 248,028. (No model.)

To all whom it may concern:

Be it known that I, THOMAS WHITE, of Peekskill, in the county of Westchester and State of New York, have invented a certain 5 new and useful Improvement in Horse-Detachers, of which this is a complete specification.

This invention is designed as an improvement upon the horse-detacher shown and de-10 scribed in Letters Patent No. 362,341, issued to me, Thomas White aforesaid, May 3, 1887.

The pivotal rods employed in the said horse-detacher for locking the bolt-carrying levers in place are apt to rattle during the motion of 15 the vehicle to which the device is applied.

The object of my present improvement is to provide a locking and releasing device for this purpose, none of the parts of which can rattle, while an equal or greater reliability of action 20 is assured.

To this end in the improvement each bolt-carrying lever is connected to a part of the whiffletree by a knuckle-jointed rod, which, when straightened, locks the trace-bolt in 25 place, and to which a flexible line is connected for folding it and thus retracting the trace-bolt, substantially in the manner hereinafter described, and as pointed out in the claim.

Reference is to be had to the accompanying 30 drawings, forming a part of this specification, in which similar letters of reference indicate corresponding parts in all the figures.

Figure 1 is a plan view of a horse-detacher embodying my improvement when the traces 35 are fastened. Fig. 2 is a plan view of one end of the said detacher when the trace is released, and Fig. 3 is a front view of the same.

The whiffletree A may be provided with end 40 sockets to receive the trace-bolts B, and the levers C, to which the bolts B are hinged, be pivoted to rigid brackets D on the whiffletree,

as in my previous patent, No. 362,341, before mentioned.

The free end of each bolt-carrying lever C is directly connected to the whiffletree A, or 45 to an attachment thereof, by a knuckle-jointed rod, E, the ends of which are pivoted to the said lever and whiffletree, respectively.

The two rods E on the ends of the whiffletree are connected together, preferably at their 50 joints, by a cord or line, F, which is guided by pulleys G, arranged on the inside of the whiffletree, near the ends thereof, and an operating cord or line, H, is attached to the middle of the connecting cord or line F, and is carried 55 to an easily-accessible point in the body of the vehicle, substantially as in my previous patent, No. 362,341.

The jointed rods E when straightened, as in Fig. 1, securely lock the trace-bolts against accidental retraction; but in case of a runaway by pulling on the line H the rods E are simultaneously folded at their joints, as illustrated in Fig. 2, thereby swinging the pivotal levers C, retracting the bolts B, and releasing the 65 traces, as by my original form of detacher referred to.

Having thus described my invention, I claim as new and desire to secure by Letters Patent—

The combination, with the whiffletree having end sockets, the pivotal levers, and the trace-bolts hinged thereto, of knuckle-jointed rods connecting the pivotal bolt-carrying levers with the whiffletree, and a draw line or lines for folding the knuckle-jointed rods and 75 retracting the trace-bolts, substantially as described.

THOMAS WHITE.
